DESIGN FOR A TRADE MARK.

The Schedule referred to in these Letters Patent and making part of the same.

TO ALL WHOM IT MAY CONCERN:

Be it known that I, JOHN M. The design represents two apartments, A and B, with a door, C, partially opened between them. In the apartment A there is represented a man seated on a lounge, at his left side a portable safe and a pistol, at his right, bags, kegs, and a window. In the apartment B, a man near the door C, and a man leaving the room at the door D.

What I claim as my invention, and desire to secure by Letters Patent, is—
